UNITED STATES PATENT OFFICE.

FOREST H. HARTZELL, OF DAYTON, OHIO, ASSIGNOR TO THE CROWN HARDWARE
MANUFACTURING COMPANY, OF DAYTON, OHIO, A CORPORATION OF OHIO.

SELF-HEATING IRON.

1,139,862.

Specification of Letters Patent. Patented May 18, 1915.

Application filed May 6, 1914. Serial No. 836,805.

To all whom it may concern:

Be it known that I, FOREST H. HARTZELL, a citizen of the United States, residing at Dayton, in the county of Montgomery and 5 State of Ohio, have invented certain new and useful Improvements in Self-Heating Irons, of which the following is a specification.

My invention relates to smoothing irons 10 for hand operation and particularly to irons of self heating type.

The object of the invention is to simplify the structure of such devices, whereby they will not only be cheapened in construction, 15 but will be more efficient in use, easily operated and controlled and unlikely to get out of repair.

A further object of the invention is to provide an improved form of burner for the 20 use of liquid fuel, and further to provide means for protecting the hand of the operator from the intense heat generated by such burner.

With the above primary and other incidental objects in view as will more fully appear in the specification, the invention consists of the features of construction, the parts and combinations thereof or their equivalent as hereinafter described and set 30 forth in the claims.

Referring to the drawings Figure 1 is a longitudinal sectional view of the assembled iron. Fig. 2 is a perspective view of the burner removed from the body of the iron. 35 Fig. 3 is a detail view of the perforated member of the burner before being compressed showing by dotted lines the degree of compression. Fig. 4 is a transverse sectional view of the burner. Fig. 5 is a transverse sectional view of the assembled iron. Fig. 6 is a bottom plan view of the removable cover body of the iron. Figs. 7 and 8 are detail, transverse and longitudinal and 40 sectional views respectively of the main body of the iron with the cover and burner removed.

Like parts are indicated by similar characters of reference throughout the several views.

50 In constructing the iron, there is employed a main body 1 of the usual proportions and shape having therein a recess or chamber 2 for the reception of the burner. At the rear of the chamber 2 the main body 1 is extended as at 3 so as to form a cup shaped

receptacle to form a generating cup in which the fuel may be placed for initially priming the burner. The rear wall of the chamber 2 is slotted as shown at 4, Fig. 7, in which the burner is slidingly mounted.

The burner consists of a head 5 grooved on its opposite sides as indicated at 6 to engage the sides of the slot 4. Projecting horizontally from said head 5 into the chamber 2 is a tubular burner member 7 closed at 60 its extremity and perforated on its under side. This hollow burner member is formed from a cylindrical tubular member, such as is shown in Fig. 3 provided at one extremity with a closure cap 8, by flattening the cylindrical tube throughout a portion of its length leaving at the open end a cylindrical portion 11, to engage with the head 5. The flattened or ovate shape of the perforated portion of this burner member causes the 65 flame to be distributed more evenly over a wider space upon the bottom of the main body 1, thereby increasing the efficiency of 70 the device.

Supported upon the head 5 is a fuel supply conduit 9 communicating with a reservoir 10. This supply conduit 9 passes through the head 5 above the plane of the perforated burner member and is continued within the chamber 2, first downward to a 75 plane below the level of the perforated burner member then horizontally parallel with the burner member in a plane below but at one side thereof. The conduit is formed into a U shaped bight below the 80 burner member and returns on the opposite side thereof to a point adjacent to the head 5 and passes upward and thence through the head and downward as at 12 to a point opposite the open end of the burner member, 85 where it is provided with the usual needle valve operated by the adjusting wheel 13. The liquid fuel is thus passed from the burner through the conduit in close proximity to the burner where it is transformed 90 into a gaseous product by the heat before 95 admitted to the burner.

The upper edge of the main body 1 is notched or recessed as shown at 14 to permit the escape of the products of combustion. 100 It has been found by experience that when using irons of this type as usually constructed, the operator is rendered uncomfortable by the subjection of his hand to 105 heat arising from the iron.

The removable cover for the main body of the iron comprises a plate 15 having a down turned flange 16 about the margin thereof spaced outward from the side walls of the chamber 2 and overlapping the notches or recesses 14 in the upper edges of said walls. Secured to the inner side of the plate 15 and located within the chamber 2 is an auxiliary cover plate 17 having a down turned 10 marginal flange 18 spaced inward from the side walls of the chamber 2 and extending below the level of the notches or recesses 14.

Interposed between the main cover 15 and the auxiliary cover 17 is a layer 19 of asbestos or other heat resisting material. The 15 double cover plate 15 and 17 with the interposed layer of the non-conductive material reduces the tendency of the heat to radiate upward and confines the heat to the main body 1 of the iron where it is most effective. The down turned flanges 16 and 18 form a tortuous passage for the products of combustion which are thereby directed downward and away from the hand of the operator. In addition to these protective features, there is provided a shield 20 spaced 25 above the cover plate 15 to which it is connected by down turned lugs or ears 21 at each end of the shield. This forms between the shield and the cover plate 15 an intermediate air space 22, by which the heat radiated by the iron is further dispersed before reaching the hand of the operator. The opposite ends of the shield 20 are curved 30 upward as at 23 to form supports for the handle 24 to be grasped by the hand of the operator. As shown in the drawings, the cover plates 15 and 17 and likewise the shield 20 are preferably though not necessarily formed from sheet metal.

To secure the removable cover in place there is attached to the outer side of said cover at the rear thereof, a plate 25 having rearward extending fingers 26 adapted to engage holes 27 in the rear wall of the chamber 2 on each side of the slot 4. At the forward end of the body 1 there is provided a pivoted finger or button 30 normally registering with the slot 29 in the apex of the cover, but which may be turned to a position out of alignment with said slot 29 to secure the cover in position. As shown in Figs. 1, 5 and 6, the rear end of the cover plate 15 is provided with a down turned flange 28 55 which rests upon the upper side of the burner head and closes that portion of the slot 4 above the burner when the cover is in place.

Having thus described my invention, I 60 claim:

1. In a self heating iron, a chambered main body, a burner therein for liquid or gaseous fuel comprising a perforated tubular member flattened throughout a portion 65 of its length and cylindrical throughout the

remainder of its length, a reservoir for fuel, and a conduit leading from the reservoir and extending in parallel relation with the perforated member at one side thereof and in a plane below that of the perforations of the member, then formed into a U-shaped bight beneath the burner member and returning on the opposite side thereof in parallel relation therewith, but in a plane beneath that of the perforations of the member and discharging into the cylindrical extremity of the burner member. 70 75

2. In a self heating iron, a chambered main body, a perforated burner member located therein comprising a cylindrical tubular member flattened throughout a portion of its extent, a fuel conduit formed into a U-shaped bight extending in parallel relation with the perforated burner member and the bottom of the main body, said fuel conduit discharging into the perforated burner member, and a fuel reservoir with which the conduit communicates. 80 85

3. In a self heating iron, a chambered main body, a heating member therein, a cover for the chambered body, an elongated shield plate having its opposite ends upturned, a handle supported by the upturned ends, and integral dependent lugs connecting the shield plate with the body cover 90 but spaced away therefrom. 95

4. In a self heating iron, a chambered main body, a heating member therein, a cover for the main body, a shield plate located in spaced relation above the cover, integral dependent tongues connecting the plate with the cover, the opposite ends of the plate being bent upward, and a handle interposed between the upturned ends of the plate. 100 105

5. In a self heating iron, a chambered main body having a recessed upper edge, a heater therein, and a cover plate having a down turned marginal flange extending below the level of the recesses of the upper edge of the main body but spaced away therefrom. 110 115

6. In a self heating iron, a chambered main body having a recessed upper edge, a heater therein, a cover plate for the main body, and a down turned flange carried by the cover plate extending within the chamber of the main body in parallel relation with but spaced inward from the side walls of the main body extending below the level of the recesses in the upper edge of the main body. 120 125

7. In a self heating iron, a chambered main body having a recessed upper edge, a heater therein, a cover plate for the main body, and double parallel down turned flanges carried by the cover plate extending below the level of the recesses in the edge of the main body between which the upper edges of the main body project, the flanges 130

being arranged in parallel relation with but spaced away from the side walls of the main body.

8. In a self heating iron, a chambered main body having a recessed upper edge, a heater therein, a cover plate having down turned flanges inclosing the upper edges of the walls of the main chamber but spaced away therefrom, an auxiliary cover plate secured to the under side of the cover plate and a down turned flange on the auxiliary cover plate extending within the main body in parallel relation with, but spaced away from the side walls of said main body.
- 15 9. In a self heating iron, a chambered main body having a recessed upper edge, a heater therein, a cover plate having a down turned flange inclosing the upper edges of the walls of the main chamber, but spaced away therefrom, an auxiliary cover plate secured to the under side of the main cover plate, a down turned flange on the auxiliary cover plate extending within the main body in parallel relation with, but spaced away from the side walls of said main body, and a layer of nonheat conductive material located intermediate the main and auxiliary cover plates.
10. In a device of the character described, 30 a main body, a burner for liquid or gaseous fuel supported thereon including a tubular member formed by collapsing a cylindrical

tube throughout a portion of its length the collapsed portion of the tube having perforations in one of the flattened walls thereof, and a fuel supply conduit discharging into the uncollapsed portion of the tube.

11. In a device of the character described, a main body, a burner for liquid or gaseous fuel supported thereon including a tubular member flattened horizontally throughout a portion of its length, the flattened horizontal portion being perforated on its under side, and a fuel supply conduit discharging into the unflattened portion.

12. In a device of the character described, a main body, a burner for liquid or gaseous fuel supported thereon including a tubular member of substantially elliptical cross section throughout a portion of its length, and 50 cylindrical throughout the remainder of its length, the elliptical and cylindrical portions being substantially in axial alinement one with the other, the elliptical portion being perforated, and a fuel supply conduit 55 discharging into the cylindrical portion.

In testimony whereof, I have hereunto set my hand this 17th day of April A. D. 1914.

FOREST H. HARTZELL.
